VEST CONSTRUCTION

Rudolf Hirschfeld, Bronx, N. Y.

Application January 15, 1938, Serial No. 185,114

4 Claims.

(CL 2—102)

My present invention relates generally to apparel, and has particular reference to an improved vest construction.

Primarily, the present improvements are designed to enhance the appearance and fit of a man's full-dress vest, particularly of the sleeveless variety, but it will be understood that certain phases of my invention are not necessarily restricted to a vest of this particular type.

10 In a vest of the kind to which my invention is applicable, there are a pair of front portions adapted to overlap when the vest is worn. One of the portions is provided with a series of buttons, or similar male fasteners, and the other portion is provided with a series of corresponding buttonholes, or equivalent female fasteners. The vest is also provided with a neckband portion, which merges with the front portions through conventional lapels extending in a more or less downwardly convergent manner.

15 In accordance with my invention, the front portion which carries the buttons is provided with a trouser-engaging tab which is secured at a point coincident with the center of one of the buttons, preferably at a point coincident with the center of the uppermost button.

20 One feature of my invention lies in coupling this trouser-engaging tab, which is adapted to exert a central downward pull upon the front of the vest, with an anchoring tab secured to the vest at the rear center of the neckband portion.

25 Another feature of my invention lies in the particular arrangement of the trouser-engaging tab with respect to a flap carried by and behind the button-carrying portion, to cover the rear parts of the buttons. More particularly, I provide a slit in this flap through which the free end of the trouser-engaging tab may extend. 30 This arrangement, coupled with the novel means of securing the trouser-engaging tab, provides a construction of unusual simplicity and efficiency.

35 I achieve the foregoing objects and such other objects as may hereinafter appear or be pointed out in the manner illustratively exemplified in the accompanying drawing, in which:

Figure 1 is a front elevational view of a vest embodying the features of the present invention;

40 Figure 2 is a fragmentary rear view of the button-carrying front portion;

45 Figure 3 is a view similar to Figure 2 with a portion of the button-covering flap broken away; and

50 Figure 4 is an enlarged cross sectional view

55 of the button-carrying front portion 11, showing the buttonholes 17 and the anchoring tab 23.

60 The front portion 11 of the vest is provided with a series of buttonholes 17, and the anchoring tab 23 is secured to the vest at a point coincident with the center of one of the buttons.

65 The anchoring tab 23 is secured to the vest at a point coincident with the center of one of the buttons, and the free end of the anchoring tab 23 is secured to the vest at a point coincident with the center of one of the buttons.

70 The anchoring tab 23 is secured to the vest at a point coincident with the center of one of the buttons, and the free end of the anchoring tab 23 is secured to the vest at a point coincident with the center of one of the buttons.

75 The anchoring tab 23 is secured to the vest at a point coincident with the center of one of the buttons, and the free end of the anchoring tab 23 is secured to the vest at a point coincident with the center of one of the buttons.

80 The anchoring tab 23 is secured to the vest at a point coincident with the center of one of the buttons, and the free end of the anchoring tab 23 is secured to the vest at a point coincident with the center of one of the buttons.

85 The anchoring tab 23 is secured to the vest at a point coincident with the center of one of the buttons, and the free end of the anchoring tab 23 is secured to the vest at a point coincident with the center of one of the buttons.

90 The anchoring tab 23 is secured to the vest at a point coincident with the center of one of the buttons, and the free end of the anchoring tab 23 is secured to the vest at a point coincident with the center of one of the buttons.

95 The anchoring tab 23 is secured to the vest at a point coincident with the center of one of the buttons, and the free end of the anchoring tab 23 is secured to the vest at a point coincident with the center of one of the buttons.

100 The anchoring tab 23 is secured to the vest at a point coincident with the center of one of the buttons, and the free end of the anchoring tab 23 is secured to the vest at a point coincident with the center of one of the buttons.

105 The anchoring tab 23 is secured to the vest at a point coincident with the center of one of the buttons, and the free end of the anchoring tab 23 is secured to the vest at a point coincident with the center of one of the buttons.

110 The anchoring tab 23 is secured to the vest at a point coincident with the center of one of the buttons, and the free end of the anchoring tab 23 is secured to the vest at a point coincident with the center of one of the buttons.

115 The anchoring tab 23 is secured to the vest at a point coincident with the center of one of the buttons, and the free end of the anchoring tab 23 is secured to the vest at a point coincident with the center of one of the buttons.

120 The anchoring tab 23 is secured to the vest at a point coincident with the center of one of the buttons, and the free end of the anchoring tab 23 is secured to the vest at a point coincident with the center of one of the buttons.

125 The anchoring tab 23 is secured to the vest at a point coincident with the center of one of the buttons, and the free end of the anchoring tab 23 is secured to the vest at a point coincident with the center of one of the buttons.

130 The anchoring tab 23 is secured to the vest at a point coincident with the center of one of the buttons, and the free end of the anchoring tab 23 is secured to the vest at a point coincident with the center of one of the buttons.

135 The anchoring tab 23 is secured to the vest at a point coincident with the center of one of the buttons, and the free end of the anchoring tab 23 is secured to the vest at a point coincident with the center of one of the buttons.

140 The anchoring tab 23 is secured to the vest at a point coincident with the center of one of the buttons, and the free end of the anchoring tab 23 is secured to the vest at a point coincident with the center of one of the buttons.

145 The anchoring tab 23 is secured to the vest at a point coincident with the center of one of the buttons, and the free end of the anchoring tab 23 is secured to the vest at a point coincident with the center of one of the buttons.

150 The anchoring tab 23 is secured to the vest at a point coincident with the center of one of the buttons, and the free end of the anchoring tab 23 is secured to the vest at a point coincident with the center of one of the buttons.

155 The anchoring tab 23 is secured to the vest at a point coincident with the center of one of the buttons, and the free end of the anchoring tab 23 is secured to the vest at a point coincident with the center of one of the buttons.

160 The anchoring tab 23 is secured to the vest at a point coincident with the center of one of the buttons, and the free end of the anchoring tab 23 is secured to the vest at a point coincident with the center of one of the buttons.

165 The anchoring tab 23 is secured to the vest at a point coincident with the center of one of the buttons, and the free end of the anchoring tab 23 is secured to the vest at a point coincident with the center of one of the buttons.

170 The anchoring tab 23 is secured to the vest at a point coincident with the center of one of the buttons, and the free end of the anchoring tab 23 is secured to the vest at a point coincident with the center of one of the buttons.

175 The anchoring tab 23 is secured to the vest at a point coincident with the center of one of the buttons, and the free end of the anchoring tab 23 is secured to the vest at a point coincident with the center of one of the buttons.

180 The anchoring tab 23 is secured to the vest at a point coincident with the center of one of the buttons, and the free end of the anchoring tab 23 is secured to the vest at a point coincident with the center of one of the buttons.

185 The anchoring tab 23 is secured to the vest at a point coincident with the center of one of the buttons, and the free end of the anchoring tab 23 is secured to the vest at a point coincident with the center of one of the buttons.

190 The anchoring tab 23 is secured to the vest at a point coincident with the center of one of the buttons, and the free end of the anchoring tab 23 is secured to the vest at a point coincident with the center of one of the buttons.

195 The anchoring tab 23 is secured to the vest at a point coincident with the center of one of the buttons, and the free end of the anchoring tab 23 is secured to the vest at a point coincident with the center of one of the buttons.

most button 18, extends also through the tab 23. In this way, the employment of the tab 23 does not in the least interfere with the convenient insertion, locking, unlocking, or removal, of the buttons 18.

Of primary importance is the fact that the downward pull, exerted by the tab 23 when the vest is worn, is focused at exactly the correct point for imparting a smooth, taut and well-fitting appearance to the vest. It has been found in practice, that, where a trouser-engaging tab is secured between the buttons of the vest, or at other points, the downward pull that is exerted upon the vest not only fails to impart the desired smoothness to the vest, but frequently impairs the appearance of the vest by producing undesired "breaks" or transverse wrinkles, as a result of which tabs of this character have frequently proven to be more of a nuisance than anything else, and are often not put into use by the wearer.

The desirable effects produced by the present trouser-engaging tab are enhanced by the corresponding provision at the rear center of the neckband portion 10 of an anchoring tab 25 (see Figure 1). This tab is preferably provided with a buttonhole 26, and is adapted to be hooked onto the rear collar button. This tab may be secured in position by any convenient means, preferably being stitched over the turned back ends 27 of the neckband portion 10, the ends 27 being available for taking in or letting out the neckband to fit the vest to the size and shape of any particular wearer.

35 The conjoint use of the anchoring tab 25, and the trouser-engaging tab 23, exerts an accurately central longitudinal tension upon the vest to hold the latter always in smooth well-fitting position.

40 It will be understood that the buttons need not necessarily be of the removable type shown in the drawing. However, this type is customarily used in connection with the full-dress vests, to facilitate laundering. In order to cover and conceal the rear parts of the buttons, particularly the locking elements 21, a flap 28 is secured to the portion 12 behind the latter. In accordance with my invention, this flap is provided with a slit 29 through which the free end of the trouser-engaging tab 23 may be passed, as shown most clearly in Figures 2 and 4. If the tab were not passed outwardly through this slit, it would be pocketed behind the flap 28. In order to make it available for engagement with the trousers of the wearer, 45 it is passed outwardly through the slit 29.

The details of assembly of the various parts, except as otherwise stated herein, are not material to the present invention. However, it may be pointed out that a customary and convenient

mode of assembly is shown in Figure 4 in which it will be observed that the portion 12 is provided with a lining 30, while the flap 28 is unlined, and is secured at its upper end by means of stitches 31.

5 In general, it will be understood that changes in the details herein described and illustrated for the purpose of explaining the nature of my invention, may be made by those skilled in the art without departing from the spirit and scope of the invention as expressed in the appended claims. 10 It is, therefore, intended that these details be interpreted as illustrative and not in a limiting sense.

Having thus described my invention and illustrated its use, what I claim as new and desire to 15 secure by Letters Patent is:

1. In a vest, front portions one of which is provided with a series of buttons, the other with corresponding buttonholes, a trouser-engaging tab secured to the button-carrying portion, and a 20 flap carried by and behind said button-carrying portion and behind said tab, said flap having a slit below the upper end of said tab through which the free end of said trouser-engaging tab may extend. 25

2. In a vest, front portions one of which is provided with a series of buttons, the other with corresponding buttonholes, a trouser-engaging tab secured to the button-carrying portion at a point coincident with the center of one of said 30 buttons, and a flap carried by and behind said button-carrying portion and behind said tab, said flap having a slit below the upper end of said tab through which the free end of said trouser-engaging tab may extend. 35

3. In a vest, front portions one of which is provided with a series of buttons, the other with corresponding buttonholes, a trouser-engaging tab secured to the button-carrying portion at a point coincident with the center of the uppermost button, and a flap carried by and behind said button-carrying portion and behind said tab, said flap having a slit below the upper end of said tab through which the free end of said trouser-engaging tab may extend. 40

4. In a vest, a pair of front portions adapted to be overlapped when the vest is worn, one of said portions being provided with a series of buttonholes, the other portion being provided with a series of eyelets adapted to accommodate removable buttons for engagement by said buttonholes, a trouser-engaging tab secured to the eyeleted portion at a point coincident with one of said eyelets, and a flap carried by and behind said eyeleted portion and behind said tab, said flap having a slit below the upper end of said tab through which the free end of said trouser-engaging tab may extend. 45

RUDOLF HIRSCHFELD.
